UNITED STATES PATENT OFFICE.

LUELLA K. SUTTLE, OF LOS ANGELES, CALIFORNIA.

TABLE CRUMB-SWEEPER.

1,236,122.

Specification of Letters Patent. Patented Aug. 7, 1917.

Application filed May 16, 1916. Serial No. 97,881.

To all whom it may concern:

Be it known that I, LUELLA K. SUTTLE, a citizen of the United States, residing at Los Angeles, in the county of Los Angeles and State of California, have invented new and useful Improvements in Table Crumb-Sweepers, of which the following is a specification.

This invention relates to a sweeper and particularly pertains to a sweeping device for gathering crumbs.

It is another object to form a device of the character described by a special construction so that the various parts will be of simple design and may be readily assembled.

Another object is to provide a simple and effective casing for the operating mechanism.

Another object is to provide a specially constructed handle which is mounted upon the casing of the sweeper in an interlocking manner so that the component parts of the handle will be securely held by the same means which fastens the handle to the case.

It is a further object to provide a crumb sweeper which is formed of few parts, may be readily assembled, and manufactured at small cost.

Other objects will appear hereinafter.

The invention is illustrated in the accompanying drawings in which:

Figure 1 is a view in plan and shows the top portion of the sweeper when assembled.

Fig. 2 is a plan view illustrating the bottom of the sweeper as assembled and showing the correlation between the traction wheels and the sweeper brush.

Fig. 3 is a view in perspective illustrating the assembled sweeper in a position suitable for operation.

Fig. 4 is a view in perspective illustrating in a composite manner the correlation between the various parts of the sweeper casing and the manner in which they are assembled, and with the brush shown in a fragmentary manner.

Fig. 5 is a perspective view of one of the false end members used in the construction of this device.

Fig. 6 is a view in perspective illustrating one of the combined longitudinally extending side walls and sweeping receptacles.

Fig. 7 is a perspective view showing the form and construction of one of the end wall members.

Fig. 8 is a view in perspective illustrating the detachable top with which the sweeper is provided.

Fig. 9 is a view in transverse vertical section as seen on a line through the brush and the sweeping compartments, and illustrates the correlation between the sweeping brush and its adjacent compartments.

Fig. 10 is a fragmentary perspective view showing the sweeper handle and its mounting upon one of the side walls.

Fig. 11 is a view in plan illustrating the handle shown in Fig. 10, and indicating in dotted lines the manner in which it is secured to the side of the sweeper.

Fig. 12 is a fragmentary view in perspective showing the end of the handle member with parts broken away to illustrate the composite construction.

Fig. 13 is a transverse section taken on the line 13—13 of Fig. 11.

Referring to the drawings more particularly, 15 indicates the body portion of the sweeper having side members 16 and 17 of approximately twice the length of the end members 18 and 19. A handle 20 is secured to the side member 16 and a detachable lid or cover 21 is positioned substantially over the side members and adapted to pass around the handle member.

Reference being had to Fig. 4 it will be seen that the side walls 16 and 17 are formed with arcuate longitudinally extending outer portions 22 which connect along their lower edges with a horizontally disposed floor 23. The inner edge of the floor members are turned upwardly and form an arcuate shield 24 which is concentric with the center of rotation of the sweeper brush 25. As particularly shown in Fig. 9, the members 16 and 17 are of like configuration and are so disposed in relation to each other that their arcuate shield members 24 lie upon opposite sides of the brush 25 and are each equally spaced from the brush core 26 and concentric therewith. It will be further observed in the same figure that the outer walls 22 extend upwardly the approximate height of the sweeper brush and that these walls are concentric with the brush.

The side members 16 and 17 are so formed that their walls 24 do not extend the full length of the walls 22 but terminate short of the ends of said walls. Upturned ears 27 are formed along the terminating edges of the floor members 23 and are so disposed in

relation to the ends 28 of the wall 24 that the false end members 29 and 30 may be held between the ends 28 and the ears 27. The false end 30 is particularly illustrated in Fig. 5 of the drawing and is shown as being formed with arcuate end portions 31 and 32 which conform to the inner surface of the walls 22 of the side members 16 and 17. The upper and lower marginal edges 33 and 34 of the end 30 are parallel and when in position are adapted to extend horizontally. The upper edge has a pair of outwardly projecting tangs 35 and 36 which are spaced a distance from each other and an equal distance either side of the longitudinal center of the sweeper. The lower edge 34 of the end member is formed with an outwardly extending tang 37 which is of a length similar to that of the upper tangs. The tang 37 is formed with a semi-circular perforation 38 having its outer edge 39 parallel to the end of the tang for a purpose which will hereafter be set forth. While I have thus described the false end member 30, it will be understood that the member 29 is of a similar construction and mounting.

The brush 25 is cylindrical in shape and is formed with a central core or shaft 26 which is shown as comprising a pair of wires twisted together in a manner to securely hold the bristles in place and provide a rigid central axle for the brush. The terminating ends of the shaft 26 are adapted to extend through openings 40 in the center of the false end members 29 and 30. Spur gears 41 are secured upon the ends of the shaft 26 after they have passed through the bores 40. Gears 42 are mounted upon rotating spindles 43 upon which the tractor wheels 44-47 inclusive are fixedly mounted. When the ends of the spindle 43 are in position within bores 48 and 49 formed upon opposite sides of the bore 40 in the members 29 and 30, the gears will be in mesh and the movement of the tractor wheels will act to rotate the brush 25.

The spindles 43 are mounted at their outer ends in perforations 50 and 51 formed in the end caps 18 and 19 which are provided to incase the gears and the tractor wheels. As particularly shown in Fig. 7 of the drawings, the end casings are formed with an end wall 54 which is of substantially the same inner marginal configuration as that of the false walls previously described. A flange 55 extends outwardly and at right angles to the end wall 54 and is adapted to fit snugly over the walls 22 and the floors 23 of the side members 16 and 17. A pair of rectangular slots 56 and 57 are formed in the lower horizontally disposed portion of the flange 55 through which a portion of the frictional tires 58 with which the tractor wheels are provided, extend to engage the surface being swept.

A cover 59 is provided for the sweeper and is shown in Fig. 8 of the drawings as being formed with a body portion 60 which is in a single plane and which has arcuate downturned flanges 61 and 62 which, when in position, conform to the surface of the walls 22 of the side members 16 and 17. An open-ended slot 63 is formed at substantially the longitudinal center of the flange 62 and is of the proper dimension to accommodate the handle portion 20 mounted within the side member 16. The cover member 21 is preferably formed of sheet metal having an inherent resiliency so that its flange portions will grip the sides of the sweeper when in position.

It will be noted that there are no separate securing or fastening members used in the construction of this device. This feature of design has been attained by forming semi-circular engaging perforations 64 and 65 adjacent the ends of the arcuate walls 22 of the side members and the semi-circular opening 39 formed within the tang 37 of the members 29 and 30 as hereinbefore described. These perforations are adapted to register with obtrusions 66, 67 and 68 which are formed as a part of the casing members 55. The obtrusions are stamped out of the metal and are in the shape of a portion of a cone having a square base, said base being adapted to positively engage the square face of the perforations with which it registers.

In order that the device may be easily handled and operated the handle 20 is provided and secured in the manner which will presently be described to the arcuate wall 22 of the side member 16. The handle 20 may be of any desired configuration which will permit its being conveniently grasped. It, however, is novel in construction in that it is composed of a pair of telescoping members 69 and 70 which are arranged in relation to each other as particularly shown in Fig. 13 of the drawings. In this figure it will be noted that each one of the members is composed of body portions 70 and 71 and side flanges 72 and 73 which overlap each other and are of a corresponding width. The side flanges 72 and 73 of each of the members 70 and 71 extend longitudinally a distance from the body portion of the handle and terminate within tangs 74-77 inclusive. These tangs are of a width slightly less than that of their main side portions 72 and 73 and thus form a shoulder 78 which abuts against the surface of the member 22 when in position. As particularly illustrated in Fig. 10 the tangs are passed through rectangular perforations 79 and 80 formed parallel to each other and through the arcuate wall 22. When so positioned they are bent in opposite directions to each other to secure them in place.

When the device is to be assembled, the

false end walls 29 and 30 are disposed as illustrated in Fig. 4 and have the brush 25 positioned between them with the terminating ends of the core 26 extending through their openings 40 as previously described. 5 Next, the driving gears 41 are positioned upon the ends of the core and suitably secured thereto. The side members 16 and 17 are then positioned over the arcuate ends 31 and 32 of the false end walls 29 and 30 and pressed inwardly until said walls are gripped between the ends 28 of the arcuate members 24 and the ears 27 which are formed integral with and upturned from the floors 23 10 of the compartments 81 and 82. When the outer walls 22 have been brought to register with the arcuate ends 31 and 32 of the false end members, the tractor wheels are positioned with one end of their spindles 43 15 extending within the perforations 48 and 49 and with their gears 42 in mesh with the gear 41 mounted to rotate with the core 26 of the brush. When the tractor wheels are in position, the end caps 18 and 19 are 20 pressed over the assembled ends of the structure previously described. As the end caps are pressed into position, the obtrusions 66-68 inclusive will be brought to register 25 with the semi-circular slots 64, 65 and 38 which are formed within the ends of the 30 side members and the false end members, respectively. When the square shoulders of the obtrusions pass within the semi-circular slots the end caps will be securely held and 35 the operating mechanism will be adequately incased. The device is now so assembled that all of its parts are rigidly fastened in a permanent manner in relation to each other. The lid member 21 may now be 40 pressed over the arcuate surface of the outer walls 22 of side members 16 and 17 and when so pressed the resilient action of the flanges 61 and 62 will cause the lid member to be 45 securely held in a closing position and in a manner to allow its ready removal.

In the operation of the device, the tractor wheels are allowed to bear against the surface to be cleaned and while the operator manipulates the device by the handle it may 50 be moved forward and backward over the surface. The tires 58 with which the tractor wheels are provided will act in a manner to cause the wheels to rotate and they in so doing will rotate their individual gears 42. 55 The gears 42 are in mesh with the gear 41 and will thus effect the rotation of the sweeper brush while the device is being moved in either direction.

Reference being had to Fig. 9 of the drawings, it will be noted that as the brush member 25 is rotated in either direction it will 60 have a sweeping action upon the surface beneath it and will throw the particles swept upwardly and over the walls 24 into the compartments 81 and 82.

The accumulation of crumbs and other sweepings may be readily removed from the sweeper by slipping the lid member 59 from its seated and resiliently held position over the arcuate faces of the side walls 16 and 17. The chambers or troughs 81 and 82 are so formed that the sweepings may be readily removed by inverting the device.

It will thus be seen that I have provided a sweeper for collecting crumbs and like sweepings which is formed of few parts of simple design and which may be readily assembled and which is easily manipulated to produce the desired result.

I claim:

1. A crumb sweeper, comprising a rotary brush, a pair of false end walls within which the brush is mounted to rotate, sweepings receptacles mounted between said end walls and adjacent the brush, said receptacles being formed with a horizontally disposed floor, an arcuate outer wall and a concentrically arcuate inner wall adapted to conform to the periphery of the brush, gears mounted upon the ends of the brush member, a pair of rollers at each end of said brush and disposed upon opposite sides of the brush gears, other gears adapted to rotate with the rollers and mesh with the brush gears, end cap members disposed over the ends of the sweepings receptacles and in a manner to inclose the rollers and gears, means formed upon the sweepings receptacles for securing said caps in place, a handle secured to the arcuate outer wall of one of the sweepings receptacles, and a resilient lid member adapted to be sprung in place over the outer walls of the sweepings receptacles and around the handle.

2. A crumb sweeper, comprising a rotary brush, means for rotating said brush, false end walls between and upon which said brush is mounted to rotate, said end walls each having parallel upper and lower marginal edges and arcuate ends and being formed with a pair of tangs extending outwardly and at right angles to the wall from the upper marginal edge and having a lower tang similar to the first-named tangs, said tang extending from the lower marginal edge of the wall and being formed with a semi-circular perforation through it, the arcuate edge of said perforation extending adjacent the wall portion, and a suitable casting within which said false end walls are mounted.

3. A crumb sweeper, comprising a brush, operating means therefor, sweepings receptacles disposed along opposite sides of said brush, a pair of end caps positioned over the opposite ends of said sweepings receptacles, said caps being formed with vertically disposed end walls having parallel upper and lower edges and arcuate ends, said edges being formed with a flange formed around and integral with said wall and at right

angles thereto, the lower portion of said flange being formed with a pair of wheel slots, the flange being provided with a plurality of obtrusions, and means formed within the wall of the sweepings receptacles with which said obtrusions are adapted to register to detachably hold said end caps in position.

4. In a crumb sweeper casing, the combination with a rotary sweeping mechanism, of a pair of side members disposed upon opposite sides of the sweeping mechanism, said side members being each formed with a floor portion and an inner and outer upwardly extending arcuate side wall formed upon arcs concentric with said sweeping member, the inner arcuate wall and the floor of each member terminating short of the outer arcuate wall at its ends, the floor of the members being formed with upwardly extending engaging tangs disposed in a manner to allow the wall of an end member to rest between the abutting end of the inner arcuate wall and the tang at each end of the wall member, the outer arcuate wall being provided with perforations, and casting end members adapted to be mounted over the ends of said side members and having means to engage the perforations.

5. A crumb sweeper, comprising a rotary sweeping mechanism, sheet metal trough members disposed each side thereof, false end wall members adapted to slidably engage the adjacent ends of said trough members and thereby hold them in spaced relation to each other, and end caps adapted to telescope over the opposite ends of said

trough members whereby the trough members and said false end members will be held together in a unitary manner.

6. A crumb sweeper, comprising a brush, a housing therefor, a pair of sheet metal trough members mounted within said housing and upon opposite sides of said brush, false end walls within said housing adapted to slidably engage said trough members and maintain them in spaced relation to each other, end caps adapted to telescope over the opposite ends of said trough members to hold them in engagement with the false end members, and a detachable cover adapted to frictionally engage the trough members and inclose the intervening space bounded by the upper edges of said trough members and the false ends.

7. In a crumb sweeper, a pair of parallel trough members having inner and outer side walls and bottom walls with the outer side walls extending beyond the ends of the inner walls and bottom wall, upturned tangs on the ends of the bottom wall spaced from the ends of the inner walls, false end walls adapted to extend between the tangs and the ends of the inner walls to close the ends of the troughs and hold the latter in spaced relation to each other, and cap members formed with marginal flanges adapted to extend over the ends of the outer walls to clamp the trough members in engagement with the false end walls.

In testimony whereof I have signed my name to this specification.

LUELLA K. SUTTLE.
